UNITED STATES PATENT OFFICE.

ALFRED D. BOARDMAN, OF SUMNER, WASHINGTON.

BOTTLE.

SPECIFICATION forming part of Letters Patent No. 562,794, dated June 30, 1896.

Application filed November 13, 1895. Serial No. 568,790. (No model.)

To all whom it may concern:

Be it known that I, ALFRED D. BOARDMAN, a citizen of the United States, and a resident of Sumner, in the county of Pierce and State 5 of Washington, have invented certain new and useful Improvements in Bottles, of which the following is a specification, reference being had to the accompanying drawing, forming a part thereof, in which similar letters of 10 reference indicate corresponding parts.

This invention relates to bottles, jugs, jars, and similar vessels, and the object thereof is to provide a vessel which having been once filled cannot be entirely emptied of its contents without leaving evidence of the fact, and thus showing that the bottle or other 15 vessel has been once used.

The invention is fully disclosed in the following specification, of which the accompanying 20 drawing forms a part, said drawing being a central vertical section of a bottle provided with my improvement.

In the accompanying drawing, I have shown my invention applied to a bottle; and in the 25 practice of said invention I provide a bottle or other vessel A, which may be of any desired form and in the upper end of which is formed a cavity or depression, as shown at B, from the center of which projects the neck C, 30 and said neck C is adapted to be closed by a cork or stopper D in the usual manner.

By means of the central depression B in the top or upper end of the bottle there is formed an annular chamber or cavity E, as clearly 35 shown in the drawing, and said annular chamber or cavity E may be of any desired size, depth, or capacity, this feature depending entirely upon the depth of the cavity or depression B, and formed at any desired point 40 in the upper wall of the annular chamber E is a small port or opening G, which is closed by a cap H, and this port or opening G and the cap H may be of any desired form, and said cap is also composed of glass or of the 45 material of which the bottle or vessel is composed.

The operation will be readily understood from the foregoing description when taken in connection with the accompanying drawing.

The bottle is filled through the neck C in the usual manner and closed by the usual plug or stopper, and whenever it is desired to discharge a portion of its contents it is only necessary to remove said stopper, when the larger portion of the contents of the bottle 55 may be discharged in the usual manner. It is intended, however, that the annular chamber E will hold a quantity of the contents of the bottle which will be much greater in value than the bottle itself; and the only way that 60 this can be got out is by breaking off the cap H and discharging the same through the port or passage G, and this operation will be evidence of the fact that the bottle has been used or once filled and emptied of its contents. 65

I may also place on the cap H a trade-mark or the name of the proprietor or manufacturer of the contents of the vessel, and this, as will be readily understood, will also constitute an additional safeguard or protection, 70 as the absence of said trade-mark or the name of the manufacturer or owner of the contents of the bottle will be additional proof that the bottle has been once used, and it will be understood that said cap cannot be broken off 75 and again replaced without leaving evidence of the fact.

My invention is not limited to the exact form, construction, and arrangement of parts shown and described, and I therefore reserve 80 the right to make all such alterations therein and modifications thereof as fairly come within the scope of the invention.

Having fully described my invention, I claim as new and desire to secure by Letters 85 Patent—

A bottle or jug, substantially as herein shown and described, in the upper end of which is formed an annular cavity or depression, from the center of which projects 90 the neck which is adapted to be closed by a cork or stopper, whereby an annular chamber or cavity is formed in the upper end of the bottle, and formed in the upper wall of the annular chamber E is a small port or 95 opening, which is closed by a cap composed of glass or similar material, whereby the small quantity of the contents remaining in

the bottle may be discharged through the small opening in the annular chamber, the mutilation of which opening will prove that the bottle has been emptied of its original 5 contents, all arranged and operating as and for the purpose set forth.

In testimony that I claim the foregoing as

my invention I have signed my name, in presence of the subscribing witnesses, this 4th day of November, 1895.

ALFRED D. BOARDMAN.

Witnesses:

JOHN B. KRAUS,

MILTON F. CLEMENTS.
